UNITED STATES PATENT OFFICE.

ARLIE G. GARDNER, OF MEMPHIS, MISSOURI.

FARM-GATE LOCK AND LATCH.

1,369,737.

Specification of Letters Patent. Patented Feb. 22, 1921.

Application filed February 28, 1919. Serial No. 279,700.

To all whom it may concern:

Be it known that I, ARLIE G. GARDNER, a citizen of the United States, residing at Memphis, in the county of Scotland and State of Missouri, have invented certain new and useful Improvements in Farm-Gate Locks and Latches; and I do hereby declare the following to be a full, clear and exact description of the invention, such as will 5 enable others skilled in the art to which it appertains to make and use the same.

This invention relates to gate latches and the primary object of the invention is to provide an improved gate latch having means 15 for automatically locking the latching bolt against accidental movement when the gate is in its closed position.

Another object of the invention is to provide an improved gate latch having means 20 for normally holding the latching bolt out of operative position against the tension of the spring until the same is swung closed.

A further object of the invention is to provide means for releasing the latch bolt 25 when the gate is swung to its closed position.

A still further object of the invention is to provide an improved gate latch of the above character, which is durable and efficient in 30 use, one that is simple and easy to manufacture, and one that can be placed upon the market at a reasonable cost.

With these and other objects in view the invention consists in the novel construction, 35 arrangement and formation of parts, as will be hereinafter more specifically described, claimed and illustrated in the accompanying drawings forming a part thereof, in which:

Figure 1 is a side elevation of the improved latch and lock, showing the same applied to a gate and the latching bolt in 40 locked position.

Fig. 2 is a similar view, showing the latching bolt in its inoperative position and the 45 gate ready to be opened.

Fig. 3 is an edge view of the gate.

Fig. 4 is a side elevation of the gate post.

Fig. 5 is a vertical section taken on the line 5—5 of Fig. 1.

Fig. 6 is a fragmentary detail view of the gate and latch, showing the latching bolt held in operative position by the trip lever.

Fig. 7 is a reverse view of the latch removed from the gate.

Referring to the drawings in detail, 55 wherein similar reference characters design-

uate corresponding parts throughout the several views, the numeral 1 generally indicates the improved lock and latch, which is adapted to be applied to the ordinary type 60 of farm gate 2 and the numeral 3 indicates the gate post. The gate 2 may be of any preferred construction, and as shown consists of the vertical uprights 4 and the horizontal spaced panels or boards 5.

The latch and lock 1 comprises a metallic frame 6 having a front U-shaped section 7 and rear vertical strips 8. The front and rear sections 7 and 8 are bolted together and to the panels 5, as at 9. The strips 8 are 70 placed directly in alinement with the legs of the U-shaped member 7 which form a guide for the sliding latching bolt 10, which protrudes beyond the outer face of the gate. A horizontal cross bar 11 is bolted or otherwise secured to the U-shaped member 7 adjacent to the upper end thereof and has pivotally secured thereto by means of the pivot pins 12 the operating hand lever 13, which extends above and below the cross bar. The 75 bolt 10 carries an outstanding headed pin 14, which is fitted in the slotted end 15 of the lever.

The upper edge of the U-shaped member 7 is notched to provide a plurality of ratchet 80 teeth 16, and the lever 13 has pivotally secured thereto a locking dog 17, which is adapted to engage the teeth 16 and hold the latching bolt 10 in its forward position against rearward movement. A triangular 85 shaped lever 18 is pivotally connected to the hand lever 13 at one angle thereof by means of a pivot pin 19 adjacent to the upper end thereof and a link 20 has the terminals thereof secured respectively to the triangular lever 18 and the pawl 17 adjacent to the free end thereof. Thus it will be seen that when the hand lever 13 is grasped and the lever 18 swung on its pivot, the dog 17 is raised out of engagement with the ratchet 90 teeth.

A contractile coil spring 21 has the terminals thereof secured respectively to the forward vertical bar 4 of the gate and to the latching bolt 10 intermediate the ends 105 thereof and normally holds the bolt in its forward projecting position.

A trip lever 22 having a substantially upwardly extending vertical portion 23 and a substantially downwardly extending vertical portion 24 and an intermediate horizontal connecting portion 25 is pivotally 110

connected by means of a pivot pin 25 to an angle bracket 26 secured to the side of the gate adjacent to the forward edge thereof. The pivot pin extends through the trip lever 5 and connecting portion of the downwardly extending vertical leg of the horizontal connecting portion and the upper leg 23 constitutes a weight to normally hold the horizontal portion 25 in engagement with the 10 upper surface of the locking bolt 10. The outer edge of the locking bolt 10 has the upper edge thereof notched to provide a shoulder 27 and when the bolt 10 is slid rearwardly by means of the hand lever 13, the 15 same is held in its retracted position by means of the trip lever 22, the horizontal portion 25 thereof engaging behind the shoulder 27 which holds the bolt against the tension of the coil spring 21. The gate post 20 3 is provided with an aperture 28, which constitutes a keeper for the sliding bolt 10. An outstanding pin 29 is secured to the gate post above the aperture 28 and this pin constitutes a means for rocking the trip lever, so 25 as to raise the horizontal portion 25 thereof from engagement with the shoulder 27 so as to allow the latching bolt 10 to move outwardly under the influence of the coil spring 30 21 into the aperture 28, when the gate is swung closed.

The gate swings open in one direction, this being toward the right in Fig. 3. After the gate has been opened and is again 35 closed the pin 29 engages the upstanding end portion of the sleeve of the lever 22 and moves it out of engagement with the latch bar 10 thus releasing the latch bar so that the latch bar may be moved by the spring 21.

40 In operation of the improved device, the lever 13 is grasped and the triangular shaped lever 18 swung on its pivot, which raises the dog 17 out of engagement with the teeth and the lever 13 is then operated so 45 as to slide the bolt rearwardly against the tension of the coil spring and when the same has been fully retracted, the horizontal portion 25 of the trip will drop down and engage the shoulder 27 and thus hold the 50 latching bolt against movement under the influence of the spring 21. When the gate is swung closed, the pin 29, as stated, will engage the outer surface adjacent to the free end thereof of the legs 23 and 24 and 55 thus swing the same on its pivot and raise the horizontal portion 25 out of engagement with the shoulder and allow the same to move forwardly under the influence of the spring 21 and into the aperture 28, 60 which holds the gate in its closed position. The latch is then absolutely prevented from being accidentally operated by means of the

pawl or dog 17 which holds the same against movement.

In practice, I have found that the form of 65 my invention illustrated in the accompanying drawings and referred to in the above description, as the preferred embodiment, is the most efficient and practical; yet realizing the conditions concurrent with the 70 adoption of my device will necessarily vary, I desire to emphasize that various minor changes in details of construction, proportion and arrangement of parts may be resorted to, when required without sacrificing 75 any of the advantages of my invention as set forth.

What I claim as new is:

1. A gate latch and lock comprising a frame, a sliding bolt carried by the frame, 80 a lever pivoted intermediate its ends to the frame, means operatively connecting the lower end of the lever with the sliding bolt, a segmental rack bar mounted on the frame, a pivoted pawl carried by the lever and arranged to engage the teeth, and means carried by the lever for operating the pawl, as and for the purpose specified. 85

2. The combination with a gate and post, 90 of a latch therefor including a frame, a spring pressed bolt, a shoulder formed on the forward end of the bolt, a trip lever pivoted to the gate including upwardly and downwardly extending arms and a horizontal intermediate portion normally in the 95 path of the shoulder, a keeper secured to the gate post, and an outstanding pin arranged above the keeper in the path of the upwardly disposed arm for swinging the trip on its pivot to raise the horizontal part 100 of the trip above the shoulder to permit the bolt to be projected into engagement with the keeper.

3. A gate latch and lock comprising a U-shaped frame having depending arms, a 105 cross bar extending between and connected with the arms of the U-shaped frame, an actuating lever pivotally connected with the cross bar and extending above and below the frame, a sliding bolt extending transversely of the U-shaped frame and connected with the lower end of the actuating lever, the head portion of the U-shaped frame being cut to provide rack teeth, and means carried by the upper portion of the lever 110 for engaging the rack teeth to releasably retain the lever in an adjusted position. 115

In testimony whereof I affix my signature in presence of two witnesses.

ARLIE G. GARDNER.
